UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,136,369.

Specification of Letters Patent. Patented Apr. 20, 1915.

Application filed April 3, 1914. Serial No. 829,236.

To all whom it may concern:

Be it known that I, CHARLES F. Root, a citizen of the United States of America, residing at Ravenna, in the county of Portage and State of Ohio, have invented certain new and useful Improvements in Safety Devices, of which the following is a specification.

This invention relates to certain new and useful improvements in safety devices, and relates more particularly to safety devices used in connection with staying machines.

The object of the invention is to provide means to prevent the follower or head and anvil or die from contacting in cases where the hand of the operator or any other obstruction may be interposed between said parts.

The invention in one form thereof comprises a ratchet bar attached to the head of the press which carries the follower, and means to operate a pawl so that the pawl will engage with the teeth of the bar and support and lock the head against downward movement. In other words, when the pawl becomes engaged with the teeth of the bar, it locks the head and prevents same from completing its stroke toward the anvil. When this takes place, the rotation of the crank shaft is stopped or the belt that transmits power to the crank shaft is thrown off, and as a result in case the operator's hand is interposed between the follower and die and jaws of the anvil, the hand is not crushed or injured in any way since the head which carries the follower cannot complete its stroke but is supported and held by the pawl against downward movement.

In the drawings: Figure 1 is a side elevation of an ordinary staying machine to which the invention is applied; Fig. 2 is a front view; Fig. 3 is a plan view of the anvil to which the invention is applied; Fig. 4 is an end view of the anvil partly broken away and in section, showing a plate attached thereto; Fig. 5 is a section on the line 5—5 of Fig. 3; Fig. 6 is a section on the line 6—6 of Fig. 3; and Fig. 7 is a side elevation of the device of Fig. 3.

The frame 1, of the machine supports an L-shaped arm 2 thereon, a shaft 3 being journaled in the arm and carrying a crank 4 that has a crank pin 5, to which a link 6 is attached at its upper end, the lower end 58 of the link being attached to a stud 7 which

is secured to a head 8. The crank shaft 3 reciprocates the head 8 in the usual ways 9. A follower 10 is carried by the head and is adapted to be brought in contact with the jaws 11 and 12 of the anvil 13. The jaws 11 and 12 have their upper portions tapered and conjointly form an inverted V-shape, and have their lower portions inclined as shown at 14 and 15. The jaws are loosely fitted in a slot 16 and rest upon a plate 17, 60 that is of concavo-convex cross-section.

A groove 18 is formed in the side of the anvil and a shaft 19 is fitted in the groove so as to be capable of rotation therein. The shaft 19 is held in place in groove 18 by the 70 clips 20, 21 and 22, which clips have their free ends formed to conform to the shape of the shaft as depicted in Fig. 4. An enlarged groove 23 is formed in the anvil coaxial with the groove formed for the journals of the shaft 19. Apertures 24 and 25 are provided in the anvil and extend at right angles to the latter and communicate with the slots 16 by means of vertical apertures 26 and 27 which lead up into the 80 bottom of the slot 16 and communicate with the apertures 24 and 25. Arms 28 and 29 of L-shape are disposed within the apertures 24 and 25 and have the free ends of their vertical portions projecting through the 85 apertures 26 and 27 to support the plate 17. The arms 28 and 29 may be made integral with or secured to the shaft, as desired.

A lever 30 having a boss 31 is secured to the shaft 19 by a feather key 32 which permits the anvil to be slidably adjusted within the limits of the enlarged groove 23. The anvil is seated in a head block 33 on its front end and is supported at its rear end by a standard 34 which has a cap 35 formed to 95 fit over the anvil. It will be apparent that the anvil can thus be longitudinally adjusted to accommodate itself to the follower for boxes having different depths. A standard 36 is fastened to the bed of the machine 100 1 and has its upper end bifurcated to provide a guide for a lever 30. A link 37 is connected at its lower end to the free end of the lever 30 and its opposite end is pivotally connected to an arm 38 which is secured to a 105 shaft 40 that is journaled in the bracket bearings 41 and 42. A rack bar 43 is secured to the top of the head 8, and has its teeth engageable by a pawl 44 secured to the shaft 40 so that the tooth of the pawl is 110

- disposed in front of and in position to engage the teeth of the rack bar. It will be apparent that the shaft 40 is adapted to rotate in the bearings 41 and 42 throwing the pawl 44 in and out of engagement with the rack bar when movement is imparted to the shaft. A plate 47 is fastened on the end of the anvil to hold the jaws from endwise movement.
- 5 10 The lever 30 and the link 37, when given movement, partially rotate the shaft 40, throwing the pawl 44 into contact with the teeth of the rack bar 43. The pawl 44 is normally held out of engagement with the rack bar 43 by a spring 45 which constantly exerts downward tension on the lever 30 to maintain the pawl out of engagement with the teeth of the rack bar. When the follower is reciprocated to contact with the
- 15 20 jaws 11 and 12, the jaws are forced downward against the plate 17 which in turn is forced against the ends of the arms 28 and 29 partially rotating the shaft 19 and imparting an upward movement to the lever 30, link 37, and arm 38 thereby moving the pawl 44 to engage with the teeth of the rack bar 43. If any obstruction, such as the operator's hand or the like, is interposed between the follower and the jaws 11 and 12, pressure
- 25 30 will be brought to bear upon the arms 28 and 29 of the shaft, forcing the pawl into engagement with the teeth of the rack bar supporting it and preventing it from making its stroke, and the belt which transmits power to the crank shaft will thus be thrown off and the machine stopped.
- 35 The weight of the lever 30 and its connections to the pawl, normally keep the jaws 11 and 12 in their upward position as shown in Fig. 5, so that when pressure is brought to bear upon the jaws 11 and 12 they are forced in a downward direction contacting with the plate 17 which is forced in contact with the end of the arms of the shaft 19, forcing it to
- 40 45 rotate as described above for the purpose of throwing the pawl in and out of engagement with the rack bar.
- In order to provide for the operation of the machine in performing its function of placing the stays on the boxes, the rack bar 43 is made of such a length that when the follower 10 is within, for instance, a sixteenth of an inch, above the jaws 11 and 12, the rack will be below the tooth 46 of the pawl and when movement is imparted thereto by the pressure of the follower upon the jaws, the lip instead of moving into engagement with the rack bar 43 will move over the top of the rack bar without engagement therewith, thus permitting the follower and jaws of the anvil to be rigidly pressed together.
- 50 55 60 What is claimed is:
1. In combination with an anvil and a reciprocatory head, a rack bar secured to the
- head and projecting upwardly therefrom, a pivoted pawl for engagement with the teeth of the rack, means connected to the pawl normally holding the pawl out of engagement with the rack teeth, and means borne by the anvil for actuating said connecting means to move the pawl into engagement with the rack teeth to hold the head against movement, said anvil means being operable by the head engaging an object extraneous to the work and interposed between the head and anvil.
- 70 75 80 85 90 95 100 105 110 115 120 125 130
2. In combination with an anvil and a reciprocatory head, a rack bar secured to the head and projecting upwardly therefrom, a pivoted pawl for engagement with the teeth of the rack, and means associated with the anvil and pawl whereby said pawl is moved to engage the rack to hold the head against movement by an object interposed between the head and anvil, said rack being of such length so that when the head contacts with the anvil the pawl will move over the upper end of the rack without engaging the latter.
3. In combination with an anvil and a reciprocatory head, a locking member on the head, means to engage the locking member to hold the head against downward movement, and means carried by the anvil and actuated by an object extraneous to the work and in the path of travel of the head to actuate the means which engage the locking member.
4. In combination with an anvil and a reciprocatory head, a locking member on the head, means to engage the locking member to hold the head against downward movement, and means associated with the anvil and with the means which engage the locking member to actuate the means which engage the locking member, said means which engages the locking member being movable past the same without engagement therewith upon contact of the head with the work upon the anvil.
5. In combination with an anvil and a reciprocatory head, a jaw movably carried by the anvil and normally projecting thereabove, a shaft carried by the anvil, arms on the shaft engaging the jaw, a lever connected to the shaft, a rack secured to the head and extending upwardly therefrom, a pivoted spring held lever rigidly connected to the shaft, a pivoted pawl for engagement with the rack, and means connected to the lever and pawl whereby rocking of the shaft will move the pawl toward the rack.
6. In combination with a reciprocatory head, an anvil having a part of the working face thereof movable, a lock on the head, and means operated by said movable part of the anvil to engage the lock and hold the same against downward movement when an obstruction extraneous to the work is interposed between the head and anvil, said

means, when the work on the anvil and head contact being moved past the lock without locking the lock.

7. In combination with a reciprocating head and an anvil having a movable part thereon, a member extending above and connected to the head, and means in connection with said movable part and operated thereby which means when the work on the anvil and head contact allows the head to move downward without engagement with the means, and which when an obstruction extraneous to the work is interposed between the head and anvil will engage the head and lock the same against downward movement.

8. In combination with a reciprocatory head and an anvil having a movable part thereon, a notched member connected to the head and extending thereabove, mechanism to engage the notched member to lock the same and the head against downward movement, and means operated by said movable part to effect movement of said mechanism.

9. In combination with a reciprocatory head and an anvil having a movable element associated with the working face thereof, locking means for the head, means to operate the locking means from said element when an object is interposed between the head and element, and means on the head to engage the locking means.

10. In combination with a reciprocatory head and an anvil having a movable element associated therewith, locking means for the head, means to operate the locking means from said element, and means on the head to engage the locking means, when an obstruction extraneous to the work is interposed between the head and element, and to enable the locking means to move past said means on the head when the head and the work on the anvil contact.

11. In combination with a reciprocating work engaging head and an anvil, means associated with the head to lock the head against downward movement on its working stroke, and means associated with the anvil

engageable with an object extraneous to the work and interposed between the head and anvil to actuate said locking means to locking position upon the interposition of the object between the head and anvil and to enable the head to complete its working stroke without engagement with the locking means when there is a free space between the head and the work on the anvil.

12. In combination with a reciprocating head and an anvil, means to lock the head against downward movement on its working stroke and means forming a part of the working face of the anvil for operating the locking means whereby when an object extraneous to the work is interposed between the operating means and the head the operating means can move the locking means to locking position.

13. In combination with a reciprocating head and an anvil, means to lock the head against downward movement, depressible means forming a part of the working face of the anvil and actuatable by an object extraneous to the work and interposed between same and the head to operate the locking means and means connecting the locking means to the depressible means to enable the latter to operate the locking means.

14. In combination with a reciprocating head and an anvil, operating means associated with the anvil, and locking means associated with the head and connected to the operating means to lock the head against downward movement upon interposition of an object extraneous to the work between the anvil and head, said locking means allowing contact of the work on the anvil and head when there is free space between the work and head.

In testimony whereof I affix my signature in presence of two witnesses.

CHARLES F. ROOT.
